UNITED STATES PATENT OFFICE.

WILLIAM H. BUSER AND BURRELL L. SHAW, OF DENISON, TEXAS.

CAR-DOOR FASTENING.

SPECIFICATION forming part of Letters Patent No. 223,705, dated January 20, 1880.

Application filed October 22, 1879.

To all whom it may concern:

Be it known that we, W. H. BUSER and B. L. SHAW, of Denison, in the county of Grayson and State of Texas, have invented a new and valuable Improvement in Universal Car-Door Fastening and Cleat; and we do hereby declare that the following is a full, clear, and exact description of the construction and operation of the same, reference being had to the annexed drawings, making a part of this specification, and to the letters and figures of reference marked thereon.

Figure 1 of the drawings is a representation of a side view of a car, showing our improved fastener applied. Fig. 2 is a vertical section thereof, and Fig. 3 is a horizontal section of the same.

This invention has relation to improvements in fastenings for sliding car-doors; and the nature of the invention consists in certain novel arrangements and constructions of the devices used, as will be hereinafter more fully set forth.

In the annexed drawings, the letter A designates a car-door sliding edgewise in ways or guides a, and closing a doorway in the side B of the car. When fully open, the door abuts against a stop, a', or other equivalent device, and is prevented thereby from being thrown out of its ways.

C indicates a metallic box let into the side of the car so as to be flush therewith and not interfere with the opening of the door. This box has in its face a deep L-shaped recess, a², one branch of which (lettered b) is horizontal and the other (lettered b') vertical.

At the middle of the branch b' is a vertical bolt, c, upon which vibrates horizontally a vibrating block, D, having the shoulders e e', and at its free end the rabbeted lug f, having a perforation, i.

The block D has free vertical movement from top to bottom of the vertical branch of the recess a² and the reverse, and, being at the upper end of the said branch, may be swung back into the horizontal branch b. In this position the outer face of part D, which may be called the "staple-block," is flush with the face of the box C and with the side of the car, so that the door slides past it without interference.

When the staple is swung out at right angles to the side of the car, the door being closed, the staple-block drops automatically to the bottom of the vertical branch of the re-

cess a², in which position the shoulders e e' bear against the face of box C at each side of the said vertical branch, and the rabbeted lug f extends out sufficiently beyond the outer face of the door to receive a staple, E, fixed thereto.

It will be observed that the body g of the staple-block bears against the edge of the door, and, being of a size to fit nicely in the bottom of branch b', cannot vibrate or play. Consequently it opposes an insuperable obstacle to the opening of the door.

The hasp is secured to the staple-block by means of a padlock, and prevents the said block from being raised and swung into the horizontal branch of the recess.

When the staple-block is in the horizontal branch of the recess a² it is locked therein by means of swing-button G, pivoted at l to the box C and arranged in a sector-shaped recess, j, in its face. This button may be swung upward on its pivot l to admit the block D, and downwardly after its admission to confine it.

The parts of our improved fastener are all of metal, either cast or wrought, or part may be cast—as, for instance, the box C—and the balance wrought.

What we claim as new, and desire to secure by Letters Patent, is—

1. In a sliding-door fastening, the combination, with the car B and sliding door A, of the box C, having the L-shaped recess a², the rod c in the vertical branch of said recess, and the vertically-movable horizontally-vibrating staple-block D, having the staple-eye f, adapted to be engaged with a hasp on the door, substantially as specified.

2. The combination, with the car B and its sliding door A, of the box C, having the L-shaped recess a² and the shallow sector-shaped recess j, the rod c in the vertical branch of recess a², the staple-block D, having a vertical and horizontally-vibrating movement on said rod, and the swing-button G, vibrating in recess j and locking the block D in and releasing it from the horizontal branch of recess a², substantially as set forth.

In testimony that we claim the above we have hereunto subscribed our names in the presence of two witnesses.

WILLIAM HARRY BUSER.
BURRELL LOUIS SHAW.
